UNITED STATES PATENT OFFICE.

WELLINGTON A. KOCH, OF PLAINFIELD, NEW JERSEY.

TRAFFIC SIGNAL.

1,422,210.

Specification of Letters Patent. Patented July 11, 1922.

Application filed October 10, 1921. Serial No. 506,664.

To all whom it may concern:

Be it known that I, WELLINGTON A. KOCH, a citizen of the United States, residing at Plainfield, in the county of Union, State of New Jersey, have invented certain new and useful Improvements in Traffic Signals; and I do hereby declare the following to be a full, clear, and exact description of the invention, such as will enable others skilled in the art 10 to which it appertains to make and use the same.

This invention relates to new and useful improvements in signals and particularly to traffic signals.

15 One object of the invention is to provide a traffic signal so constructed that the driver of an approaching vehicle will have his attention attracted to the signal at the same time the motion in the proper direction, according to the traffic regulations.

Other objects and advantages will be apparent from the following description, when taken in connection with the accompanying drawings.

25 In the drawings:

Figure 1 is an elevation of a traffic signal made in accordance with the invention.

Figure 2 is a top plan view, and

30 Figure 3 is an enlarged sectional detail view through the upper portion of the post.

Referring particularly to the accompanying drawings, 10 represents a post of suitable size and material which is preferably hollow, and which is circular in cross section. The upper portion of the post has a cylindrical transparent glass casing 11, and above this casing is a rectangular frosted glass casing 12, each of the four vertical side faces of which has formed thereon the legend "Keep to the right," in black letters, so that they may be readily seen in the daytime as well as at night. On top of the casing 12 is mounted a frosted spherical globe 13, within which is disposed the lamp 14 which 40 may be an electric lamp coil, gas or the like. The light from this lamp is adapted to pass downwardly so as to shine through the casings 11 and 12.

45 Mounted within the casing 11 is a cylind-

rical frosted glass drum 15, having painted 50 or otherwise formed on its outer face the circular series of dark arrows 16, all pointing in one direction, either to the right or to the left around the drum. These arrows may be readily seen through the clear glass 55 casing 11 in the daytime and are also visible by means of the light from the lamp 14, at night. The drum 15 is mounted on a revolving platform 17 which has the gear 18 driven by the gear 19 of the motor 20, all of which 60 are mounted within the upper portion of the post.

Attention is particularly directed to the fact that each side face of the casing 12 has a stationary legend directing traffic toward 65 the right and that below this stationary legend is the moving signal indicating the direction that should be taken by the vehicle. This moving signal will attract the attention of the driver of the car and if he 70 should fail to note the stationary legend, the moving arrows 16 which rotate very slowly, will be sure to be seen. The globe 13 may be of any color desired, as also may the casing 12.

75 While I have illustrated the legend on the faces of the member 12 as "Keep to the right", this may be any other legend referring to traffic directions, such as "One way street", "Do not enter", or the like.

80 Instead of the arrows 16, I may form on the rotatable glass drum the representations of hands, pointing in either direction, or other symbols desired.

85 What is claimed is:

1. A traffic signal comprising a support, a stationary direction legend on the support, and a constantly moving indicator adjacent the legend.

90 2. A traffic signal including a post, a stationary illuminated direction legend on the post, and a constantly moving signal associated with the legend in its direction designation.

95 3. A traffic signal including a post having a transparent ring, a stationary illuminated direction legend on the post above the ring, and a constantly moving signal associated

with the legend in its direction designation and movable behind the transparent ring and visible through said ring.

4. A traffic signal including a post having
5 a translucent upper stationary portion on
which is formed a direction legend, a trans-
parent ring mounted below the direction
legend, and a constantly rotating signal
movable behind the transparent ring and

having a direction signal thereon visible 10
through the ring and associated with the
legend in its direction designation.

In testimony whereof, I affix my signa-
ture, in the presence of two witnesses.

WELLINGTON A. KOCH.

Witnesses:

Mrs. E. FAIRCLOUGH,
Mr. H. LAMP.
